ANGUS R. GROSS, OF BALTIMORE, MARYLAND.

DESIGN FOR A COWL-LIGHT FOR AUTOMOBILES, &c.

59,212.

Specification for Design.

Patented Oct. 4, 1921.

Application filed February 18, 1921. Serial No. 446,171. Term of patent 14 years.

To all whom it may concern:

Be it known that I, ANGUS R. GROSS, a citizen of the United States, residing at Baltimore, State of Maryland, have invented a new, original, and ornamental Design for a Cowl-Light for Automobiles, &c., as shown in the accompanying drawing, forming part of this specification.

In said drawings:—Figure 1 is a side view of the cowl light. Fig. 2 is a front end view thereof. Fig. 3 is a rear end view thereof.

The design consists of an approximately

short T-shaped body portion having a longitudinal transverse cylindric portion A and a depending substantially cylindric portion B, the light or front end of the body portion having a jewel or glass C, and the rear end of the body portion having a tapered polygonal sided finial D.

I claim:

The ornamental design for a cowl light for automobiles, &c., substantially as shown and described.

ANGUS R. GROSS.
